UNITED STATES PATENT OFFICE.

FRANK J. IRVING, OF BUFFALO, NEW YORK, ASSIGNOR TO PINES WINTERFRONT COMPANY, OF CHICAGO, ILLINOIS, A CORPORATION OF DELAWARE.

THERMOSTATIC VALVE DEVICE FOR RADIATOR SHUTTERS, ETC.

Application filed December 31, 1924. Serial No. 758,976.

To all whom it may concern:

Be it known that I, FRANK J. IRVING, a citizen of the United States, and resident of Buffalo, in the county of Erie and State 5 of New York, have invented certain new and useful Improvements in Thermostatic Valve Devices for Radiator Shutters, Etc., of which the following is a full, clear, concise, and exact description, reference being 10 had to the accompanying drawings, forming a part of this specification.

My invention relates to a new and improved thermostatic valve device which has for its principal field of utility the control of 15 suction or pressure operated radiator shutters for automobiles. This type of radiator shutter generally utilizes manifold suction for its operation, although it may utilize other fluid suction or pressure, and the present 20 thermostatic valve device has particular application to such shutters for controlling this fluid suction or pressure.

One of the objects of the invention is to provide a thermostatic valve device having 25 an improved manner of adjustment for adjusting the device for operation at different temperatures. This adjustment is very simple to set and is relatively foolproof.

Another object of the invention is to 30 provide a thermostatic valve device which will have an improved method of attachment to the water conduit connecting the radiator and the engine whereby it can be mounted very quickly and is readily adjustable and adaptable to mounting on conduits of different sizes and at different angles and locations on these conduits. This is of considerable advantage in that it provides a fitting which is universally applicable to all 35 water cooled cars.

Another object is to provide a thermostatic valve device in which the number of moving parts has been reduced to a minimum, and which is very simple and inexpensive to construct.

In the accompanying drawing illustrating a preferred embodiment of my invention:

Figure 1 is a fragmentary view showing the radiator, engine, water conduit, etc., of 50 a typical motor car installation, the shutter being illustrated diagrammatically in section;

Figure 2 is a longitudinal sectional view through the thermostatic valve device;

Figure 3 is a plan view of the same;

Figure 4 is an enlarged transverse sectional view through the valve housing, and

Figure 5 is a similar view showing the valve in open position.

In Fig. 1 the engine of an automobile 60 power plant is indicated at 8, the radiator for the cooling circuit at 9, and the upper water conduit for connecting the two at 11. In installing the present automatic shutter mechanism, the shutter attachment 12, comprising the pivoted shutters and operating cylinder is mounted on the face of the radiator in any suitable manner. The series of pivoted shutters 13 are all operatively connected through a link 14 which is responsive 70 to the application of suction to the operating chamber 15. This operating chamber may consist of any desired form of expandible and contractible chamber, of either the piston, diaphragm or sylphon type, although 75 it generally consists of a conventional cylinder and piston. Suitable spring means is arranged normally to close the shutters, this spring means being overcome by the operating cylinder 15 upon the application 80 of suction thereto. This suction is drawn from the intake manifold 16 through suction tubes 17 and 18, the former extending from the manifold to the thermostatic valve unit, and the latter extending from this thermo- 85 static valve unit to the operating cylinder 15.

This thermostatic valve unit is adapted to be mounted at any desired point on the upper water conduit 11, as shown in Fig. 1. This is the preferred location for the valve 90 unit inasmuch as this conduit first receives the heated water from the engine 8, but it is conceivable that the valve unit might be mounted on the lower water conduit connecting the bottom of the radiator with the 95 engine or pump.

This thermostatic valve unit comprises a relatively long, narrow plate 21, which serves as the base or frame piece on which are assembled the thermostatic strip and the 100 valve housing. The thermostatic element consists of a strip 22 of thermostatic metal which is secured in a trough-like depression in the end of the plate 21. This trough-like depression is formed by turning up lateral flanges 23 along the edges of the plate, which flanges strengthen this end of the plate and protect the edges of the 105

thermostatic strip metal 22. A tongue 25 extends from the other end of the plate 21 for mounting the device on the water conduit 11. This tongue is of arcuate cross section to engage snugly over the cylindrical contour of the water conduit. A clamp 26, either of one-piece or two-piece construction, clamps the tongue 25 to the conduit, with the thermostatic strip 22 extending lengthwise of the conduit and in close proximity thereto for ready absorption of heat. If the hood or any other adjacent parts of the car should form an obstruction to the mounting of the thermostatic valve unit on the top 15 of the water conduit, it can be shifted down to a position along the side of the water conduit, or even under the same, if necessary. Likewise, because of the one-point attachment, this thermostatic valve device 20 can be secured to a bowed or curved length of water conduit; and it may be supported in any inclined, or even a vertical, position without binding of the parts. This readily adapts the unit to universal mounting on 25 practically all water-cooled cars.

The plate 21 is composed of aluminum and thus acts as a ready conductor of heat from the water conduit to the thermostatic strip. This strip 22 is of any suitable bimetallic construction, being secured to the plate 21 at its front end by a rivet 28. This point of attachment is preferably upon a raised hump 29 punched up from the under side of the plate 21, whereby the opposite 30 end of the strip is supported above the plate 21 in position for free flexure. Supported above this free end of the thermostatic strip 35 is the valve housing 31. The plate 21 is formed with an upwardly turned extension 32, the front face of which is provided with a series of transverse ridges or corrugations 33 which are adapted to match similar ridges or corrugations 34 in the rear face of the valve housing. These ridges are held 40 in matched engagement by a thumb screw 35, the threaded shank 35' of which extends through a vertical slot 36 in the supporting extension 32 and has threaded engagement 45 in the valve housing 31. By releasing the clamping pressure imposed through this screw, the valve housing can be raised or lowered and matched with different teeth 33 in adjusting the device for different working 50 temperatures, all as I shall hereinafter describe. Narrow lateral flanges 37 extend from the sides of the supporting extension 32 and form, in effect, a vertical socket for 55 this valve housing.

This housing preferably consists of a 60 solid block of metal which is bored out from opposite ends to provide a transverse bore 38. The opposite ends of this bore are threaded for receiving nipples 39 and 41 which are screwed fast into the block for 65 providing ready connecting members for

the tubes 17 and 18. These tubes are preferably inserted into the ends of the nipples and are held therein by outer gripping sleeves 42.

The valve consists of a ball 43 which is 70 adapted to engage the end of the nipple 39. The bore in this nipple provides a right angle valve seat 44 which is adapted to have line contact with the ball valve 43. The other nipple 41 may have its end slotted, as indicated 75 at 45, to prevent the ball valve from ever effectively seating against this nipple. The bottom wall of the bore 38 intermediate these nipples is left slightly elevated, as indicated at 46, to hold the ball in axial 80 alignment with the bore of the nipple 39.

Drilled up through the bottom of the block 31 is a hole 47 which receives the valve-operating pin 48. This pin has a large lower head 49 which joins with the shank of the pin through a tapered portion 51. This head 49 is adapted to lie on the free end of the thermostatic strip 22, whereby the pin will rise and fall with the flexure of this thermostatic strip. A small leaf spring 52 has one end clamped between the side of the block 31 and a shoulder 53, on one of the nipples, the lower end of this spring having a hole 54 therein receiving the pin and normally tending to thrust the 55 pin downwardly.

With the water in the cooling system cold and the engine at rest, the radiator shutters 13 will be held closed under the action of the closing spring, as above described. With the starting of the engine, the suction created in the intake manifold will draw the ball valve 43 against the valve seat 44, thus preventing the transmission of suction to the operating cylinder 15 at this time. As the engine warms up and a larger amount of heated water is circulated up through the conduit 11, the temperature of the thermostatic strip 22 will gradually rise until, at a certain predetermined temperature, it will 100 thrust the pin 48 up against the bottom of the ball valve 43 and force it off of the seat 44 into approximately the position shown in Fig. 5. Thereupon the suction will be transmitted to the other nipple 41 and 105 through its associated tube 18 to the operating cylinder 15, which will operate to open the radiator shutters. This open condition of the shutters will continue until the temperature of the cooling system has fallen to a predetermined minimum temperature, at 110 which time the downward flexing of the thermostatic strip 22 will permit the reseating of the ball valve 43 and the interruption 115 of suction to the operating cylinder 15, whereupon the shutters 13 will automatically close to hold the engine heat or to bring the cooling system back to its desired 120 temperature. If it is desired to change the 125 temperature or temperatures at which the 130

radiator shutters open and close, the same can be accomplished through the mere shifting of the valve housing 31. The thumb screw 35 is released and the valve housing is moved upwardly or downwardly a notch or two, depending upon whether the device is to operate at a lower or higher temperature, and the valve housing is then locked in the set position by merely tightening the 10 thumb screw 35. For minor adjustments, the plate 21 is provided with a hole 56 directly under the thermostatic strip 22, as shown in Fig. 2. By inserting a pencil or pointed instrument up through this hole an 15 upward pressure may be exerted in the under side of the thermostatic strip for giving it a slightly higher normal "set." By pressing downwardly on the top of the strip it may be given a lower normal "set".

20 For repair to the valve housing or substitution thereof, the thumb screw 35 is merely withdrawn and the housing removed. It will be noted from Fig. 5 that when the pin 48 is raised to push the ball valve 43 up into 25 open position, the tapered portion 51 of the pin shank is in close proximity to, or is seating against, the lower end of the hole 47, thereby avoiding undesirable venting of atmosphere into the bore 38.

30 Having thus described my invention, what I claim is:

1. The combination with a radiator shutter having an expandible and contractible chamber for operating said shutter, of a 35 thermostatic element, a valve housing enclosing a valve and valve port, said valve controlling a conduit communicating with said chamber, said conduit preventing rotation of said valve housing, means actuated by said thermostatic element for operating said valve, and means for supporting said valve housing for adjustment relative to said thermostatic element.

2. In a thermostatic valve device for radiator shutters, etc., the combination of a supporting member, a thermostatic element carried by said supporting element, a valve housing enclosing a valve and valve port, a conduit fixedly attached to said valve housing, means actuated by said thermostatic element for operating said valve, and means permitting adjustment of said valve housing relative to said supporting member and to 50 said thermostatic element.

3. In a thermostatic valve device for radiator shutters and the like, the combination of a supporting member adapted to be mounted on some portion of the car comprising part of the cooling system, a valve housing supported by said supporting member, and thermally responsive means for actuating the valve in said housing, said valve housing being adjustable on said supporting member and carrying the valve therewith in 65 all adjustments of said housing.

4. In a thermostatic valve device for radiator shutters and the like, the combination of a supporting member adapted to be mounted on some portion of the car comprising part of the cooling system, a valve housing carried by said supporting member, a valve completely enclosed in said valve housing, thermally responsive means for actuating the valve in said valve housing, and means adjustably supporting said valve housing on said supporting member whereby the temperature limits for said valve may be shifted by adjusting the position of said valve housing on said supporting member.

5. In a radiator shutter of the type wherein in the shutters are fluid-pressure operated and thermostatically controlled, a supporting member, thermally responsive means carried by said supporting member, a valve port, a valve controlling said port under the control of said thermally responsive means, and means for shifting the relative position of said valve and said supporting member.

6. In a radiator shutter of the type wherein in the shutters are fluid-pressure operated and thermostatically controlled, a supporting member, thermally responsive means carried by said supporting member, a valve port, a valve controlling said port under the control of said thermally responsive means, and means for shifting the relative position of said valve port and said supporting member.

7. In a radiator shutter of the type wherein in the shutters are fluid-pressure operated and thermostatically controlled, a supporting member, thermally responsive means carried by said supporting member, a valve port, a valve controlling said port under the control of said thermally responsive means, and means for shifting the relative position of said valve port and said thermally responsive means.

8. In a thermostatic valve device for radiator shutters and the like, the combination of a plate, a thermostatic strip secured to said plate, a valve housing carried by said plate having a valve and valve port therein, and means adjustably supporting said valve housing permitting adjustment thereof relative to said thermostatic strip.

9. In a radiator shutter of the type wherein in the shutters are fluid-pressure operated and thermostatically controlled, a thermostatic valve unit therefor comprising a mounting member, a thermally responsive element secured to said mounting member, a supporting surface projecting from said mounting member, and a valve housing adjustably clamped to said supporting surface for adjustment relatively to said thermally responsive element.

10. In a radiator shutter of the type wherein the shutters are fluid-pressure oper-

- ated and thermostatically controlled, a thermostatic valve unit therefor comprising a mounting member, a supporting surface projecting therefrom having a plurality of projections thereon, a valve housing having projections thereon adapted to interengage with the projection on said supporting surface, and means for holding said projections in engaging relation.
- 10 11. In a radiator shutter of the type wherein the shutters are fluid-pressure operated and thermostatically controlled, a thermostatic valve unit therefor comprising a supporting member, a supporting wall disposed at an angle to said supporting member, a thermally responsive element carried by said supporting member, a valve housing carried by said supporting wall, said housing and said wall having cooperating serrations 20 in their opposing faces, and a thumb screw for holding said serrations in engagement, said thumb screw engaging in a slot in said supporting wall.
12. In a radiator shutter attachment of the type wherein the shutters are fluid-pressure operated and thermostatically controlled, a thermostatic valve unit comprising a valve housing, a passageway in said housing, a ball valve adapted to seat against said port, and a pin entering said passageway from the side thereof and operative to push said ball laterally from said valve seat.
13. In a radiator shutter mechanism of the type wherein the shutters are fluid-pressure operated and thermostatically controlled and a thermostatic valve unit therefor comprising a valve housing, a passageway in said housing, a valve port in said passageway, a valve adapted to seat against said port, a bore entering said passageway laterally, a pin in said bore operative to push said ball valve laterally from said seat, and thermally responsive means for actuating said pin.
14. In a radiator shutter mechanism of the type wherein the shutters are fluid-pressure operated and thermostatically controlled, a thermostatic valve unit therefor comprising a valve housing, a passageway in said housing, a valve port in said passageway, a valve adapted to seat against said port, a bore entering said passageway laterally, a pin in said bore operative to move said valve, and means for closing said bore when said pin is at one limit of its operating movement.
15. In a radiator shutter mechanism of the type wherein the shutters are fluid-pressure operated and thermostatically controlled, a thermostatic valve unit therefor comprising a valve housing, a passageway in said housing, a valve port in said passageway, a valve adapted to seat against said port, a bore entering said passageway laterally, a pin loosely fitting in said bore and operative by
- thrusting movement to move said valve, and means for closing said bore when said pin has been thrust inwardly.
16. In a radiator shutter attachment of the type wherein the shutters are fluid-pressure operated and thermostatically controlled, a thermostatic valve unit therefor comprising a valve housing, a passageway in said housing, a valve port in said passageway, a valve adapted to seat against said port, a pin entering said passageway and operative to displace said valve from said valve seat, a shoulder adjacent the outer end of said pin, and a leaf spring engaging said shoulder and normally thrusting said valve pin outwardly.
17. In a radiator shutter attachment of the type wherein the shutters are fluid-pressure operated and thermostatically controlled, a thermostatic valve unit therefor comprising a valve housing, a passageway in said housing, a nipple screwed into said passageway, the end of said nipple defining a valve seat, a ball valve in said passageway adapted to engage said seat, a bore communicating with said passageway laterally thereof, a pin loosely fitting in said bore, and operating by thrusting movement to displace said ball valve laterally from said valve seat, a thermally responsive device for actuating said pin, a seating portion adjacent the outer end of said pin adapted to close said bore when said pin has been thrust inwardly, and a leaf spring secured to said valve housing and engaging the outer end of said valve pin.
18. In a radiator shutter attachment of the type wherein the shutters are fluid-pressure operated and thermostatically controlled, a thermostatic valve unit therefor comprising a plate, lateral flanges on said plate defining a channel formation therein, a thermostatic strip secured to said plate and disposed in said channel formation, and a valve housing supported by said plate and comprising a valve adapted to be controlled by said thermostatic strip.
19. In a radiator shutter attachment of the type wherein the shutters are fluid-pressure operated and thermostatically controlled, a thermostatic valve unit therefor comprising a plate, lateral flanges adjacent one end of said plate defining a channel formation, an upturned supporting wall adjacent said flanges, a mounting tongue adjacent the opposite end of said plate, a thermostatic strip disposed in said channel formation, a valve housing supported on said wall and having a valve therein adapted to be responsive to said thermostatic strip, and means for clamping said mounting tongue to the water conduit of the cooling system.
20. In a radiator shutter attachment of the type wherein the shutters are fluid-pressure operated and thermostatically controlled,

a thermostatic valve unit therefor comprising a plate, a thermally responsive member carried by said plate, a valve housing carried by said plate having a valve therein adapted to be controlled by said thermally responsive member, a clamping portion projecting from said plate adapted to engage the water conduit of the cooling system, and a clamp encircling said conduit and said clamping portion.

21. In a radiator shutter attachment of the type wherein the shutters are fluid-pressure operated and thermostatically controlled, a thermostatic valve unit therefor comprising

a supporting member, a thermostatic element carried by said supporting member, a valve housing comprising a valve port and a valve controlling said port, and a valve actuating member separate from said thermostatic element and from said valve for operatively connecting said thermostatic element and said valve.

In witness whereof, I hereunto subscribe my name this 16 day of December, 1924.

FRANK J. IRVING.
